UNITED STATES PATENT OFFICE

THOMAS DUGAN, OF DENVER, COLORADO, ASSIGNOR OF ONE-HALF TO ROBERT BENJAMIN DAVIS, OF WICHITA, KANSAS

THRASHING AND SEPARATING DEVICE

Application filed November 2, 1929. Serial No. 404,292.

This invention relates to improvements in thrashers of the type employed for thrashing and separating grain of all kinds, and has reference more particularly to improvements in that type of thrasher that is employed in connection with combined harvesters and thrashers.

Thrashing machines of all kinds have heretofore been provided with rotating cylinders that are provided with a large number of teeth and which are adapted to rotate at a high speed. They have also been provided with concaves located adjacent the outer surface of the cylinder and provided with teeth that extend towards the rotating cylinder and are spaced so that the teeth of the cylinder can pass between the teeth of the concaves without actually coming in contact therewith. Such thrashers have been found to be objectionable for several reasons among which may be mentioned the fact that owing to the high speed at which the cylinder must be rotated, it absorbs an unreasonably large amount of power and when the machine is used for thrashing legumes such as beans and peas, the high speed of rotation nearly always cracks them and therefore reduces the grade and consequently the price at which the thrashed legumes must be sold.

It is an object of this invention to produce a thrashing mechanism that can readily be employed in place of the usual cylinder and concave of the ordinary thrashing devices and which shall be so constructed that it will operate at a very moderate speed whereby the power necessary for operating the same will be a minimum.

This invention briefly described consists in a thrashing device comprising two spaced shafts, each of which is provided with a plurality of sprocket wheels, or the like, that are correspondingly placed on the two shafts so as to form pairs of sprocket wheels with each pair of which an endless sprocket chain is adapted to cooperate. The sprocket chains have secured to them transversely extending bars whose outer surfaces are provided with diagonal corrugations; located beneath the lower side of the thrasher belt is a frame whose upper surface is provided with a plu-

rality of sections that correspond to the concaves of an ordinary thrashing mechanism and which are provided on their upper surfaces with transverse corrugations, or which are otherwise roughened. The concaves have slots or openings through which the separated grain may pass in a manner which will hereinafter be more fully explained.

Having thus briefly described the invention, the same will now be described in detail, and for this purpose reference will be had to the accompanying drawings in which the preferred form of the invention has been illustrated, and in which:

Fig. 1 is a longitudinal vertical section through a thrasher provided with my improved mechanism;

Fig. 2 is a section taken on line 2—2, Fig. 3;

Fig. 3 is a section taken on line 3—3, Fig. 2;

Fig. 4 is a view showing a portion of the outer surface of the thrasher belt;

Fig. 5 is a view showing a portion of the upper surface of the concaves;

Fig. 6 is a view similar to that shown in Fig. 5 and shows smooth concaves interposed between the corrugated concaves; and

Fig. 7 is a fragmentary view showing a portion of a concave constructed of heavy screen material.

In the drawings reference numeral 1 represents the frame work of a thrashing machine that is supported on wheels 2 and which is provided at its front end with a single supporting wheel 3. Secured to the frame 1 is a body or housing 4 which has been diagrammatically indicated on the drawings as it is not my intention to go into details concerning the construction of the parts that do not cooperate with my improved mechanism.

Instead of the ordinary toothed cylinder and concave, I have provided two spaced parallel shafts 5 and 6. These shafts are each provided with two or more sprocket wheels 7, which are so arranged that the corresponding sprocket wheels of each shaft are in the same plane and are adapted to be engaged by the sprocket chains 8. Encircling the shafts 5 and 6 and the sprocket wheel 7 is a thrasher belt that has been shown as consisting of two

spaced sprocket chains 8 that are connected by means of bars 9, which will be referred to as the cylinder bars because they correspond in function to the bars of the rotating cylinders. Each of the cylinder bars are provided with corrugations 10 that extend diagonally across their outer surfaces in the manner shown in Fig. 4. A canvas or other flexible member 11 is secured to the sprocket chains 10 and to the cylinder bars so as to form a flexible wall that prevents straw and other material from coming into the space between the two sides of the belt.

Located underneath the thrasher belt is a frame which is formed in part by two parallel frame members 12. The front and rear ends of these members are curved as indicated at 13 and 14, while the intermediate portion 15, is straight. The front curved portion is connected to a supporting shaft or rod 16 in such a way that it can be rotated about this shaft to a limited extent. A shaft 17 extends transversely of the machine underneath the frame members 12 and near the rear ends thereof. This shaft carries an eccentric 18 for each of the frame members, and is provided at one end with a lever or handle 19 that can be reached from the outside and by means of which shaft 17 and cams 18 can be rotated. Whenever the shaft and cams are rotated, the frame members 12 will be moved either towards or away from the thrasher belt in a manner quite obvious from the drawings. The adjusting means just described is illustrative of means for adjusting the distance between the thrasher belt and the concave frames and may be replaced by any other suitable mechanism that is adapted for this purpose. Secured to the upper surfaces of the frame members 12 are several sections of concaves which have been designated by reference numeral 20. These concaves may be made of castiron or of any other suitable material and are provided on their upper surfaces with transverse corrugations 21. In the drawings, Figs. 3, 5 and 6, these corrugations have been shown as extending at right angles to the longitudinal axes of the concave, but may be inclined with respect to this axis if desired. In between the separate corrugations, openings 22 have been provided. These openings may be circular as shown or may be longitudinal slots of such size and shape that the grain can pass through them after it has been separated. The several concaves are spaced apart by means of bars 23 which have overhanging flanges that engage the edges of the concaves in the manner shown in Fig. 3. If it is found that the grain or the legumes are being cracked or otherwise damaged by having the entire frame surface covered with concaves as shown in Fig. 5, every other concave can be removed and replaced by a smooth foraminated concave like that indicated by refer-

ence numeral 24. The concave sections that are supported on the straight portions 15 of frame members 12 are flat while the corresponding concaves supported on the curved portions 12 are transversely curved in the manner shown in Fig. 1. The curved portions 14 are provided on their concave surfaces with spaced bars or with a foraminated curved member 25 in the manner also shown in Fig. 1. The housing 4 has a downwardly extending partition 26 near the rear of the rearmost roller and the top of the housing is provided with an opening 27 near the front end. The grain or legumes to be thrashed are introduced into the machine through the opening 27 which may be located in the top as shown or in the side whichever is found to be the most suitable. The thrasher belt is moved in the direction indicated by the arrow and this will move the material to be thrashed forwardly and then downwardly into the space between the belt and the concaves where the action of the corrugations 10 and the corresponding corrugations 21 will subject the material to a rubbing action that will separate the grain or the legumes from the heads or pods. After the grain or legume have been separated they will pass downwardly through the openings 22 onto the grain pan 28 which is reciprocated by suitable means and which carries the grain onto the sieve 29 where it is subjected to the action of a blast of air produced by the rotating fan 30. The grain or legumes will fall down on the inclined surface 31 and will pass from thence to the transverse conveyor 32 which removes them from the machine to a suitable elevator not shown.

By means of the adjustment which has been described and which is formed in part by cams 18, it is possible to separate the concave surfaces from the surfaces of the thrasher belt so as to prevent the breakage of the grain or legumes and so as to get the most desirable results.

The concaves instead of having corrugations in the manner shown may be provided with roughened surfaces of almost any specific construction as, for example, semi-spherical projections may be substituted for the corrugations with good results.

In Fig. 7 I have shown a modified form of concave in which a woven wire screen 33 is substituted for the foraminated corrugated concaves shown in Fig. 5.

Owing to the fact that the machine above described provides a long passage for the grain or other material during which it is subjected to attrition, the thrasher belt can move at a speed that is slow compared with the speed of the cylinders that have heretofore been employed and for this reason a less amount of power is used and there will also be less tendency to break or hull the material that is being thrashed.

In the attached drawings I have shown an embodiment that is intended as illustrative of my invention and I do not want to be limited to the exact construction shown in the drawings and described in this specification to any greater extent than is made necessary by the state of the prior art.

Having described my invention what I claim as new is:

10 A concave for use with a thrashing device comprising, a frame comprising two spaced parallel frame members whose center portions are straight, a plurality of concave sections secured to the top of the frame, each section having its upper surface provided with spaced parallel ribs extending in the direction of the length of the frame, the spaces between the ribs being perforated, one end of the frame being supported on a stationary
15 pivot and the other being supported on rotatable cams that serve as means for adjusting the position of the frame in a vertical direction.

20 In testimony whereof I affix my signature.
25 THOMAS DUGAN.
